Primary Examiner — Karen S Acker(74) *Attorney, Agent, or Firm* — Westman, Champlin & Koehler, P.A.; James L. Young(57) **CLAIM**

The ornamental design for a fire log with burn channels, as shown and described.

DESCRIPTION

FIG. 1 is a top and front perspective view of a fire log with burn channels;

FIG. 2 is a rear elevation view, thereof;

FIG. 3 is a top and side perspective view, thereof;

FIG. 4 is a bottom and front perspective view thereof;

FIG. 5 is a top plan view, thereof;

FIG. 6 is a bottom plan view, thereof;

FIG. 7 is a front elevation view, thereof;

FIG. 8 is a right side elevation view, thereof; and,

FIG. 9 is a left side elevation view.

The dotted lines in the FIGS. are for illustrative purposes only and form no part of the claimed design.

1 Claim, 7 Drawing Sheets---
